UNITED STATES PATENT OFFICE.

WILLIAM GORTON, OF NEW YORK, N. Y.

IMPROVEMENT IN WIND-WHEEL TOYS.

Specification forming part of Letters Patent No. **152,555**, dated June 30, 1874; application filed March 21, 1874.

To all whom it may concern:

Be it known that I, WILLIAM GORTON, of the city, county, and State of New York, have invented a new and useful Improvement in Toy Wind-Wheels, of which the following is a specification:

The object of this invention is to provide means for amusing the young; and it consists in a wheel and staff, the former being provided with a sleeve-box and pin-journal, and the shaft with one or more ferrules.

In the accompanying drawing, Figure 1 is an end view of the wheel. Fig. 2 is a cross-section of the wheel on the line *x x* of Fig. 1, showing the staff and journal-pin.

Similar letters of reference indicate corresponding parts.

A is the wheel, composed of wings B, connected with center plate C, to which plate is attached the sleeve D. The wings are placed at any desired angle, so that when the wheel is moved rapidly through the air it will revolve. E is the journal-pin, screwed or driven

into the end of the staff I, as seen in the drawing. The staff is made of wood, and has a ferrule, F, to prevent the end from splitting. G is a ferrule on the other end of the staff, to give the latter a more finished appearance.

The wheel is made of sheet metal, as is the sleeve, to make the article light as well as durable.

I am aware that toy wind-wheels are not new when made of paper and attached to a stick with a pin. I do not therefore claim a toy wind-wheel broadly; but

Having thus described my invention, what I claim as new, and desire to secure by Letters Patent, is—

A toy wind-wheel, constructed as shown and described—that is, having a sleeve-box, D, journal-pin E, ferrule F, and staff I, combined and arranged as set forth.

WM. GORTON.
